UNITED STATES PATENT OFFICE

2,599,150

OVERHEAD TROLLEY WIRE MOUNTING

Lloyd L. Babcock, Torrance, and Millard L. Thorpe, Lomita, Calif.

Application April 10, 1950, Serial No. 154,988

5 Claims. (Cl. 191—23)

1

This invention relates to an electrical conductor mount of the type which utilizes a travelling contact device or trolley wheel together with one or more wire electrical conductors. This invention is particularly adapted for use in connection with certain movable appliances or motors, such as hoists, cranes, locomotives, etc.

An object of our invention is to provide a novel improved apparatus of the above character, which will provide ample insurance against accidental contact with the current carrying wires.

Still another object of our invention is to provide a novel arrangement of the current carrying wires so that the trolley wheels will effectively engage these wires to provide a good electrical contact.

A feature of our invention is to provide a novel sheath construction, partially enclosing the conductor wires, which can be assembled in sections and which will effectively hold the wires in their proper position.

Still another object of our invention is to provide a novel arrangement of the wire conductors in that they are arranged in juxtaposed pairs throughout their entire length, forming a groove in which the trolley wheel moves, or the conductors may be shaped with a longitudinal groove.

Other objects, advantages and features of invention may appear from the accompanying drawing, the subjoined detailed description and the appended claims.

In the drawing:

Figure 1 is a fragmentary side elevation of our overhead trolley wire mounting.

Figure 2 is a sectional view taken on line 2—2 of Figure 1.

Figure 3 is a fragmentary perspective view of one pair of conducting wires.

Referring more particularly to the drawing, our trolley wire mounting and construction can be applied to either a single phased or multiple phased wiring system, and may include one set of wires or more, as may be necessary.

In the drawing we have shown a single phased system with two sets of conductors. The conducting wires 1—2 are arranged in pairs and engage each other throughout their entire length, that is, they are pressed closely together by means to be subsequently described. The conductors 1—2 are preferably circular in cross-section and, consequently, when these wires are pressed together a groove 3 is formed between them and the purpose of this groove will be subsequently described. The conductors 1—2 may also be formed as an integral wire, that is, in-

2

stead of two juxtaposed circular wires, they may be integral and substantially shaped like the figure 8.

The wires 1—2 are mounted within strips 4—5, which are long wooden slats, if desired, or may be any type of insulating material. The wires are recessed within the strips 4—5, that is, they are mounted in lengthwise grooves in the strips, and an opening 6 extends to the bottom of the strip 10 to expose the grooved portion 3 of the conductors 1—2. The strips 4—5, which form a sheath to substantially enclose the conductors 1—2, are held in proper position, that is, bolted together by spaced saddle clamps 7 and by means of bolts 15 which extend through these clamps. The clamp 7 consists of a T-shaped member 7' which supports the two angles 9—9 and which rests on the top of the strips 4—5, substantially as shown. The bolt 8 extends through the angles 9—9 and 20 draws these angles tightly against the T member 7' and thus presses the strips 4—5 tightly together to hold the wires 1—2 in position. The bolt 8 extends above the strips 4—5 and thus these strips do not have to be drilled.

25 Electrical current is conducted to the wires 1—2 in the following manner:

A bolt 10 extends horizontally into the strips 4—5 and is formed with a head 11 on the inner end, which engages the side of one of the wires 1 or 2. The other wire is then pressed against the collar 12, formed of a suitable material, thus pressing the two wire conductors together and also forming an effective electrical connection. A terminal 13 is attached to the bolt 10 in the usual and well known manner. Current is conducted to the other pair of wires in the same manner.

The hoist, crane or locomotive is provided with a spring loaded arm 14, all of which is usual and 40 well known in the art. This spring loaded arm is pivotally secured to a header 15, which includes laterally spaced blocks 16 and 17. The header 15 also has a limited lateral movement on the arm 14 so as to follow any irregularities in alignment of the wires 1 or 2. These blocks are both 45 formed of a suitable insulating material (wood or other suitable material). A pair of trolley wheels 18—19 are rotatably mounted between the blocks 16 and 17. The edges of the wheels are tapered 50 or relatively sharp, as shown at 20, so as to fit into the groove 3, as shown in Figure 2. Each trolley wheel is mounted on a shaft 21, secured in the blocks 16—17. The wheels are permitted a limited amount of lateral movement on the 55 shaft 21 since a space 22 is provided on each side

of the hub of the wheel. This enables the wheels to move laterally to take care of misalignment in the wires 1-2. Electrical current is taken off from the trolley wheels 20 through the shaft 21 by means of a terminal 23 secured to the outer 5 end of the shaft.

In operation, the trolley wheels 18-19 are both pressed against the respective wires 1-2 and are pressed into the groove 3, thus forming an effective electrical contact with these wires. The trolley wheels extend upwardly through the slot 6 to engage the wires 1-2, substantially as shown. Any lateral mis-alignment in the wires 1-2 will be followed by the trolley wheels 18-19, since these wheels can move lengthwise of their 15 respective shafts 21.

Having described our invention, we claim:

1. An overhead trolley wire mounting comprising a pair of conductor wires, said wires being positioned side by side, a sheath partially enclosing the wires and pressing said wires together, clamp means securing said sheath around said wires, electrical conducting means extending through the sheath to said wires, said two wires forming a groove therebetween, and a trolley wheel engaging said groove formed by said electrical wires.

2. An overhead trolley wire mounting comprising a pair of conductor wires, said wires being positioned side by side, a sheath partially enclosing the wires and pressing said wires together, clamp means securing said sheath around said wires, electrical conducting means extending through the sheath to said wires, said two wires forming a groove therebetween, and a trolley wheel engaging said groove formed by said electrical wires, the periphery of said trolley wheel being tapered to fit in said groove between said wires.

3. An overhead trolley wire mounting comprising a pair of conductor wires, said wires being positioned side by side, a sheath partially enclosing the wires and pressing said wires together, clamp means securing said sheath around said wires, electrical conducting means extending through the sheath to said wires, said two

wires forming a groove therebetween, and a trolley wheel engaging said groove formed by said electrical wires, the periphery of said trolley wheel being tapered to fit in said groove between said wires, said trolley wheel being mounted for lateral movement relative to said wires.

4. An overhead trolley wire mounting comprising a pair of juxtapositioned electrical wires, a sheath partially enclosing said wires and pressing the wires together, said wires forming an elongated groove therebetween, said sheath having a slot in the bottom thereof extending to said electrical wires, a header, a trolley wheel rotatably mounted in said header, a shaft in the header on which said trolley wheel is mounted, the periphery of said trolley wheel being tapered to fit said groove formed by said wires.

5. An overhead trolley wire mounting comprising pairs of juxtapositioned wire conductors, each pair of wire conductors having a groove therebetween, a sheath partially surrounding said wire conductors of each pair, said sheath having a groove in the bottom thereof, extending upwardly to the wire conductors, an electrical conductor extending through the sheath and engaging said wire conductor pairs, a pair of trolley wheels, a header rotatably mounting said trolley wheels, a shaft in the header on which each of said trolley wheels is journaled, a trolley arm, said header being pivotally mounted on the trolley arm, said pivotal mounting being between said pair of trolley wheels, the periphery of said wheels being tapered to fit in said groove between the corresponding wire conductor pairs.
